UNITED STATES PATENT OFFICE.

STOCKTON BORTON, OF PROVIDENCE, RHODE ISLAND, AND JACOB C. HANKEY, OF ARLINGTON, NEW JERSEY, ASSIGNEES TO THE WILLCOX & GIBBS SEWING MACHINE COMPANY, OF NEW YORK, N. Y.

STAND FOR SEWING-MACHINES, &c.

SPECIFICATION forming part of Letters Patent No. 651,178, dated June 5, 1900.

Application filed December 6, 1898. Serial No. 698,456. (No model.)

To all whom it may concern:

Be it known that we, STOCKTON BORTON, residing in Providence, Rhode Island, and JACOB C. HANKEY, residing in Arlington, 5 Hudson county, New Jersey, citizens of the United States, have invented an Improved Stand for Sewing-Machines, &c., of which the following is a specification.

The object of our invention is to provide a simple and efficient sewing-machine table or stand of the class in which the sewing-machine is mounted so that it can be dropped down out of sight below the level of the table-top when not in use. 10 Our invention is primarily intended for sewing-machine stands and will be particularly described for such use; but it may be applied to stands or tables for other machines.

In the accompanying drawings, Figure 1 is a vertical sectional elevation of a sewing-machine stand constructed according to our improvements, the machine-leaf being shown as dropping to its depressed position when not in use and the view being taken from the rear 25 side of the table or stand. Fig. 2 is a transverse section on the line 1 2, Fig. 1, but showing the machine-leaf wholly down; and Fig. 3 is a sectional view showing the hinged leaf which supports the sewing-machine depressed 30 and the sewing-machine as provided with an inclosing cover.

The table or stand may be of any suitable type or style—that is to say, it may be of the cabinet style or of the open-stand variety—35 with or without side drawers. Some of the features of our present invention are more particularly applicable to the open variety of sewing-machine stands, and for the sake of simplicity we have illustrated in the drawings 40 one of the simplest forms of stands, consisting of a table-top A and two standards A', on one of which the fly-wheel F is carried.

The machine M is mounted on a tilting or swinging drop-leaf B, which is hinged to the 45 table-top A on the side adjacent to the fly-wheel F and which when raised to the horizontal position has its upper side flush with the surface of the table and fits an opening A² in the said table-top. A spring-latch a in 50 the table engages with the leaf B to maintain

the leaf and machine in their raised positions; but this latch is provided with a finger-piece a', Fig. 1, by which it may be drawn back to release the machine-leaf when the latter has to be depressed. A hinged cover 55 C may be employed, as shown in Figs. 1 and 2, to close the opening A² when the machine is depressed or may be turned outward, as shown by full lines in Fig. 1, to form an extension of the table-top when the machine is 60 in use.

The tilting drop-leaf B may be hinged in any suitable manner to the table. As a convenient way of effecting this we provide a pair of brackets b upon the under side or opposite edges of the leaf B and pivot these brackets at b' to brackets or arms D on the under side of the table-top A adjacent to the fly-wheel F.

With the belt E, which passes from the fly-wheel F to the grooved pulley m, we combine devices which insure the retention of the belt on the two wheels or pulleys when the machine is depressed, so that as soon as raised again the machine may be started at once. 70 We so construct these belt-retaining means, moreover, that the belts will be slightly slackened when the machine is depressed, but not to such an extent as to let the belt escape from the grooves of the pulleys. For this 75 purpose the guiding means for the belt are placed out of coincidence with or at one side of the hinging-axis b' of the drop-leaf B and are in such relation to that hinging-axis that the belt is carried past and away from such 80 axis when the drop-leaf is moved from the elevated to the depressed position. By preference we provide two guiding devices for the belt, both out of coincidence with the hinging-axis, one guiding device insuring the 85 retention of the belt on one pulley, while the other guiding device will insure the retention of the belt on the other pulley. In the present instance one guiding device—that to retain the belt on the fly-wheel—consists of a 90 pair of open hooks d, formed as extensions of the brackets D, to which the machine-leaf B is hinged. Slots or openings d' in the leaf B, through which the belt is passed to go over the pulley m on the machine, may be availed 95 100

of to act as the other guiding means to retain the belt on this pulley, as shown in Fig. 3. These openings are cut away, as at d^2 , to allow the belt to slacken when the machine is lowered. When the drop-leaf is raised, the belt is carried free of both the hooks d and the sides of the holes d' ; but when the leaf is dropped the belt enters the open hooks and is caught thereby and bears also against the edges of the holes d' , as shown in Figs. 1 and 3.

With the drop-leaf we combine an apron P , hinged at p to the under side of the table-top in front of the drop-leaf. When the drop-leaf is in its depressed position, the hinged apron P is in an approximately-vertical position, resting against the edge of the drop-leaf B and completely hiding the sewing-machine from any one looking at the stand from the front, as shown by full lines in Fig. 2. This hinged apron is acted on by springs, which may be at the hinges, as at p' , Fig. 2, tending at all times to press the apron on its hinges from the position shown in full lines in Fig. 2 to the position there shown by dotted lines. When the drop-leaf and machine are elevated, the apron is raised by the springs to the position shown by dotted lines, so as to be out of the way of the knees of the operator at the machine. This hinged spring-apron has the further function or advantage of acting as a brake to the drop-leaf and machine when released from the catch a —that is to say, when the drop-leaf is released from the said retaining-catch the leaf will come into contact with the hinged spring-apron, which will yield slowly to the weight of the drop-leaf of the sewing-machine if the operator does not retain her hold of the machine as the leaf descends.

The sewing-machine is secured to the drop-leaf B by a thumb-screw T , Fig. 3, introduced from the under side through a hole in the leaf. In order that the head of this thumb-screw may not interfere with the connecting-rod plate R or part of the driving fly-wheel, we countersink the under side of the drop-leaf, as shown at r in the drawings.

In order to protect the machine from dirt and dust, we provide an inclosing bag or cap N , of suitable fabric, preferably with an elas-

tic mouth, so that when drawn over the machine it will engage the under side of the projecting parts and inclose the whole machine effectively, Fig. 3.

We claim as our invention—

1. A drop-leaf table for sewing and other machines, having a fly-wheel and a tilting drop-leaf carrying the machine and hinged to the table on the fly-wheel side, in combination with belt-retaining means out of line with and at one side of the hinging-axis, whereby the belt is carried away from the latter when the leaf is dropped, substantially as described. 55

2. A drop-leaf stand for sewing-machines, &c., having a fly-wheel and a hinged tilting drop-leaf, in combination with fixed open hooks out of line with the axis of the hinged leaf and into which the belt can drop when the machine-leaf is depressed to retain the belt on the fly-wheel. 60

3. A drop-leaf stand for sewing-machines, &c., having a fly-wheel and a drop-leaf carrying the machine, a hinge adjacent to the fly-wheel, with open hooks out of line with the axis of the hinged leaf for the reception 75 of the belt to retain it on the fly-wheel, the drop-leaf having openings for the passage, guidance and retention of the belt on the machine-pulley, substantially as described.

4. A drop-leaf stand for sewing-machines, &c., having the drop-leaf hinged to the under side of the top of the stand, with open hooks out of line with the axis of the hinged leaf carried by the under side of the top of the stand to receive and retain the belt when 85 the leaf is depressed, with belt-retaining devices carried by the leaf to retain the belt on the machine-pulley. 80

In testimony whereof we have signed our names to this specification in the presence of 90 the subscribing witnesses.
